CLAIM

I claim the design for a vanity frame with sink top, as shown and described.

DESCRIPTION

FIG. 1 is an upper front left perspective view of a vanity frame with sink top of my design, the dashed lines representing unclaimed features;

FIG. 2 is a front plan view thereof, the rear plan view being a mirror image thereof;

FIG. 3 is a left side plan view thereof, the right side plan view being a mirror image thereof;

FIG. 4 is a top plan view thereof;

FIG. 5 is a bottom plan view thereof;

FIG. 6 is an upper front left perspective view of a second embodiment of a vanity base with sink top of my design, the dashed lines representing unclaimed features;

FIG. 7 is a front plan view thereof, the rear plan view being a mirror image thereof;

FIG. 8 is a left side plan view thereof, the right side plan view being a mirror image thereof;

FIG. 9 is a top plan view thereof; and,

FIG. 10 is a bottom plan view thereof.
